UNITED STATES PATENT OFFICE.

MAX TONK, OF CHICAGO, ILLINOIS.

DESIGN FOR A PIANO-STOOL.

SPECIFICATION forming part of Design No. 19,638, dated February 4, 1890.

Application filed December 20, 1889. Serial No. 334,442. Term of patent 7 years.

To all whom it may concern:

Be it known that I, MAX TONK, a citizen of the United States, residing at Chicago, Illinois, have invented and produced a new and original Design for Piano-Stools, of which the following is a specification, reference being had to the accompanying drawing, forming part thereof.

The drawing is a perspective view of a piano-stool showing my design.

The leading feature of my design consists in a parti-circular surface ornamentation at the corners of the seat of a stool when the seat is angular in its contour or upon the legs of the pedestal, or both.

A is a seat, which, as shown, is rectangular in its general contour, and B represents the legs thereof, which may be three or four in number. The corners of the seat have projecting parti-circular surface ornamentations C, divided into longitudinal bands c, and the sides D of the seat are plane surfaces. The

same design is carried out in the ornamentation of the legs E of the stool. Said legs have their sides E' plane surfaces, except the rosettes e. The outer faces or edges of the legs have the angular projection e', and the vertical surface thereof has the parti-circular ornamentation C, divided into longitudinal bands c, as before. Below the part C is an oval pendant F, and below the angular projection e' the face of the leg has the scroll-shaped portion G, the straight portion H, and the concave portions h. The pillar I has the longitudinal bands i at the top thereof, which harmonize with the parti-circular ornamentation C and the configuration of the pendant.

I claim—

The design for piano-stools herein shown and described.

MAX TONK.
